Mass., a corporation of Massachusetts

Application July 8, 1931, Serial No. 549,432

13 Claims.

(Cl. 20—5)

This invention relates to building material adapted to be used as a weatherproofing and an artistic covering medium for the roof and/or side walls of a building. This invention finds 5 a special application in that class of materials generally designated by the term, composition building material.

Material of this character, generally comprises a felted foundation or base, saturated or impregnated with a waterproofing compound such as asphalt or similar bitumen, and coated on one or both sides with a high melt point asphalt or similar bitumen having partially embedded therein a layer of comminuted slate, slag or the like.

At the present time, this material is produced in elements of different shapes and sizes, said elements being generally known in the trade as shingle units, strip shingles and roll roofing. These different elements find extensive use as 20 a covering medium because they can be laid to provide a weatherproof covering medium presenting an artistic design.

One of the specific aspects of the many pleasing weatherproof wall covering designs, which 25 may be produced with this type of material, is that of a brick wall with the usual mortar joints. For this purpose it has, heretofore, been customary to employ strip shingles consisting of a body having a plurality of spaced tabs in a single course defined by vertical slots. These strips are surfaced with granules in such a manner that the tab areas extending from the butt edge of the strip upward to slightly below the tops of the cut-outs shall simulate bricks, and the remaining portion of the strip shall simulate mortar.

In order that the strips may be laid to closely simulate a brick wall, they are applied in adjacent relation in each course and in overlapping relation in successive courses. One of the recognized prerequisites of the size of these strips is that their width be of at least a predetermined minimum dimension in order that a sufficiently weatherproof covering may be obtained. For example, where the strips having three inch slots are laid in successive overlapping courses and with the amount of exposure of each course being approximately three inches, it is necessary that the total width of the strip be somewhat more than twice the exposure dimension and in this instance would probably be about seven inches. Thus, the strip would have a one inch head lap so that the tops of the notches of any one course would be a sufficient distance below 50 the upper edge of a strip in a subjacent course

in order to prevent the weathering elements from driving up and under that portion above the tops of the notches and reaching the structure to be protected. Of course, with this particular construction a good deal of material is necessary to produce a weatherproofing covering.

Moreover, owing to the fact that each strip has a portion of but one row of brick simulations thereon, a considerable number of these strips must be laid to properly cover one square 10 of surface, the term "square" being generally used to designate one hundred square feet of surface. Where thirty-six by seven inch strips are laid with a one inch head lap and a three inch exposure to provide a brick simulating covering for one hundred square feet of surface to be protected, 233 square feet of material is required.

The employment of the strips embodying my invention and hereinafter particularly described 20 enables a square of wall surface to be adequately covered and simulate a brick wall by using a smaller number of strips and less material.

An object of my invention is to provide a composition building material of predetermined 25 multi-course designs which can be laid to provide a weatherproof wall covering and brick, stone, tile or other like wall simulation.

Another object of my invention is to provide a composition building material of multi-course 30 designs which require a minimum amount of time and material in laying a weatherproof stone, brick, tile or other like wall simulation.

Other objects will be apparent from the following specification and the attached drawing 35 wherein,

Figure 1 illustrates a plan view of a portion of a wall covering composed of strips, such as that shown in Figure 2;

Figure 2 is a plan view of a strip shingle embodying my invention;

Figure 3 is a plan view of a strip shingle embodying my invention and is a modification of the strip shingle shown in Figure 2;

Figure 4 illustrates a plan view of a portion of a wall covering composed of strips, such as that shown in Figure 3.

In accordance with my invention the novel covering means may be in strip shingle or roll roofing form. One embodiment of my invention 50 as shown in Figure 3, comprises a composition building strip of generally rectangular shape with side edges 11 and 12 and upper and lower edges 13 and 14 respectively. Along the bottom edge 14 of the strip, are a plurality of parallel

tab defining slots 21 spaced from each other a distance corresponding to the length of a common brick. Although the dimensions of these slots may vary within certain limits, it is preferable that their lengths correspond to the approximate depth of an ordinary brick and their width correspond to that of an ordinary vertical mortar joint of a brick wall. Spaced above the top edges of this row of slots 21 a distance corresponding to the depth of a horizontal mortar joint of a common brick wall are a plurality of slots 22. These slots 22 are located so that the longitudinal median line of each of these slots is approximately coincident with the transverse median line of the areas therebelow and between the slots 21. These slots also need not be of exact dimensions, but for the purposes of this invention it is preferred that their width be substantially the same as that of the slots 21 and their length be equal to that of a slot 21 plus the depth of a horizontal mortar joint of a brick wall. The top portion of the strip measuring from the tops of the slots 22 to the upper edge 13 of the strip is of a width preferably slightly greater than the distance from the butt edge 14 of the strip to the tops of the cut-outs 22.

In order that the lower portion of each strip when laid may simulate a plurality of courses of brick with the usual mortar joints therebetween, with a clear line of demarcation between the mortar joint and brick simulating areas, and so that the latter will stand out against the mortar joint simulating areas, the upper face of the strip or that face to be exposed may be constituted in the manner hereinafter presently described. The total upper face of the strip, namely that face to be exposed, has a coating of asphalt or similar bitumen thereon. Preferably the asphalt coating is of predetermined and equal thickness on those areas of the strip extending from the butt edge thereof to the tops of the cut-outs 21 and from the bottoms of the cut-outs 22 to a distance slightly below the tops of the cut-outs 22, corresponding to the depth of a horizontal mortar joint of a brick wall. The asphalt coating on the remaining area of the strip comprising the areas between the upper and lower limits of the lower and upper coatings respectively and between the upper edge of the strip and the upper limit of the upper coating, may also be of predetermined thickness and preferably of less thickness than that of the other coated areas. In order that the rectangular areas having the coating of greater thickness thereon and defined by the butt edge of the strip, the longitudinal edges of the slots, and the upper and lower limits of the thicker coatings may simulate bricks, the coating on these rectangular areas has partially embedded therein a layer of relatively coarse mineral granules such as comminuted slate, slag or the like of any desired brick color. The remaining or thinner coating layers adjacent thereto and of a color contrasting with that of the surfacing material need not be surfaced, but I prefer to surface these areas with talc, mica or other relatively fine grits of a color and size contrasting with that of the brick surfaced areas.

Moreover, in order that these strips may provide an efficient weatherproof covering simulating a brick wall, the strips are of such length that the respective end brick simulating areas 30 and 31 on each end of the strips are respectively less than and preferably about one quarter and three quarters the length of a full brick

simulating area. The purpose of this particular design is so that when the strips are laid in the customary manner side by side in any one course, the quarter brick simulation of one course will be immediately adjacent the three-quarter brick simulation in the same course of another strip immediately adjacent thereto and together will form a full brick simulation. Moreover, when the covering is laid in the ordinary manner of overlapping courses with the slots 21 of an overlapping course appropriately staggered with respect to the slots 22 of a subjacent course, the line of juncture between adjacent strips of the lapped portion of the subjacent course will not be in line with the slots of the overlying course, but will be covered by the brick simulating areas of the overlapping course.

These strips are laid in the customary manner to provide a brick wall simulating siding by first applying to the lowermost longitudinal area of the side wall a strip of roll roofing of approximately the same width as that of the shingle strip to be applied and having its top surface of the same color as that of the mortar joint simulating areas on the face of said shingle strip. Then a shingle strip embodying my invention is positioned thereover in a horizontal relation, with its left hand edge coinciding with a corner of the building, and appropriate fastening means such as nails are driven therethrough at any convenient points, and preferably slightly above the slots 22, and into the supporting structure.

The next strip of that course is laid by positioning it over the already applied roll roofing and locating it so that its left hand edge is closely adjacent to the right hand edge of the previously applied strip and its upper and lower edges are in substantial alignment with the corresponding limits of the previously laid shingle. At this stage, as before, it is to be fastened to the supporting structure by nails driven therethrough and into the supporting structure. Thus, the first course may be completed by a repetition of these simple operations.

After the first course has been properly laid, the next succeeding or overlapping course is applied. In order to provide an efficient weatherproof covering closely simulating a brick wall and so that the line of juncture between the adjacent strips of a subjacent course shall not coincide with either a slot in or the line of juncture between adjacent strips of a succeeding or overlapping course the initial strip of the next succeeding or overlapping course is preferably not a full or normal length strip but comprises a shorter strip having its end brick simulating areas corresponding to those on a full or normal length strip. This shorter strip is laid with its left hand edge coinciding with the corner of the building and with the left hand edge of the first full or normal length strip in the previously laid course, and its butt edge coinciding with the tops of the cut-outs 22, in the subjacent course. A plurality of nails are then driven therethrough at that portion of the strip above the tops of the cut-outs 22, and into the supporting structure. As before, a full strip is laid with its left hand edge coinciding with the right hand edge of the previously laid strip and with the upper and lower edges of the full strip being in line with respective limits of the previously laid shorter strip, and a plurality of nails driven therethrough at any appropriate place. The course may be completed with full strips in the manner heretofore out-

lined. When using strips of this particular design, care should be taken in laying a shorter strip as heretofore outlined, as the initial strip in alternate courses.

In order that all the brick simulating areas, on a strip having a portion thereof simulating a plurality of courses of bricks with the usual horizontal mortar joints therebetween, shall be of the same length and so that there shall be no possibility of a "break" in any full brick simulating area in a completed wall covering structure, I preferably provide the shingle strip illustrated in Figure 2. As shown, the strip consists of an upper portion 50 of a width preferably slightly greater than the depth of a two course brick wall with the usual mortar joints, an intermediate portion 51 of a width corresponding to the depth of a common brick and a lower portion 52 of a width equal to the sum of the depths of a brick and horizontal mortar joint, all portions being of general rectangular shape. The lengths of the portions 51 and 52 are substantially the same and approximately equal to the length of the portion 50 minus the width of a mortar joint. The upper portion 50 has side edges 53 and 54 and upper and lower limits 55 and 56 respectively, and the intermediate portion 51 has upper and lower limits 56 and 57, respectively and side edges 53 and 58. The portion 51 has therein a plurality of spaced parallel slots 60 dividing it into areas of equal lengths with the length of each area being preferably about the same as the corresponding dimension of a common brick. These slots 60 are preferably of a width corresponding to that of a mortar joint and have their bottom edges approximately coincident with the lower limit 57 of the section 51 and their top edges located on the portion 50 and spaced above the upper limit 56 of the section 51 a distance corresponding to the depth of a horizontal mortar joint. The side edge 58 is spaced inwardly from the edge 53 a distance corresponding to the width of a slot or a cut-out 60 plus one quarter the length of an area defined by two adjacent slots and the side edge 59 is spaced outwardly from the edge 54 a distance corresponding to one-quarter the length of an area defined by two adjacent slots.

The lower portion 52, of a width corresponding to a distance equal to the depth of a common brick plus the depth of a horizontal mortar joint, has upper and lower limits 57 and 61 respectively and side edges 62 and 63. Located on said lower portion and extending from the butt edge 61 thereof to a distance, below the upper limit 57, corresponding to the width of a mortar joint are a plurality of parallel spaced slots 64 whose longitudinal center lines are approximately coincident with the transverse center line of the areas thereabove defined by the slots 61. These slots 64 divide the lower portion 52 into a plurality of areas of equal lengths, with the length of each area corresponding to the length of a common brick. It is to be observed that the slots 60 and 64 are of approximately the same width and that the vertical distance from the tops of the slots 64 to the bottoms of the slots 60 is equal to the approximate depth of a horizontal mortar joint. The side edge 62 extending between the horizontal limits of the lower portion is spaced outwardly from the side edge 58 a distance corresponding to the sum of the width of a mortar joint and one-half the length of a rectangular area, defined by the slots 64; and the lateral edge 63: 68, extending from the lower limit 61 up to a

square section 65 projecting outwardly from the upper part of the portion 52, a distance corresponding to the width of a mortar joint, is spaced inwardly from the side edge 59 a distance corresponding to the width of a mortar joint plus one-half the length of a rectangular area defined by two adjacent slots 64.

The total upper face of the strip has a coating of asphalt or similar bitumen thereon and preferably the asphalt coating is of predetermined and greater thickness on those areas of the strip extending from the butt edge thereof to the tops of the cut-outs 64 and from the lower edge of the slots 60 to the limit 56, that is spaced downwardly from the upper edges of the slots 60 a distance corresponding to the depth of a horizontal mortar joint. The asphalt coating on the remaining area of the strip, comprising the areas between the upper and lower limits of the lower and upper coating respectively and between the upper limit of the upper coating and the upper edge 65, may also be of predetermined and preferably of less thickness than that of the first mentioned coating. The thicker coating areas have partially embedded therein a layer of relatively coarse grits such as crushed slate, slag or the like of any desired brick color. The remaining or thinner coatings may be left unsurfaced or surfaced with powdered talc, mica or relatively fine mineral grits of a color and size contrasting with that of the brick colored granules.

These strips may be applied with ease and despatch in the following manner:

First, a strip of roll roofing, of appropriate width and whose surface to be exposed is substantially the same as that of the mortar joint simulating areas on the strips, is laid on the longitudinal base area of the side wall to be covered. Starting at one edge of the wall, a strip such as shown in Figure 4, but severed along a line through the side edge 58 is laid over the roll roofing strip with the severed edge being substantially coincident with the edge of the wall and the strip proper being in a substantially horizontal position. Thereafter the next shingle strip of that course is laid in the same horizontal direction with its edges 53, 58 and 62 located immediately adjacent the respective edges 54, 59 and 63 in the previously laid strip. By referring to Figure 1 it will be observed that between the edges 58 and 59 and the edges 62 and 63 of the adjacent strips there is formed a slot substantially identical with the slots 60 and 64 in each strip. The second course may be laid in the usual manner, care, however, being taken in properly severing the initial strip for the second and other alternating courses so that when the corresponding strip is laid adjacent thereto in that course the lines of juncture between the edges 58 and 59 of adjacent strips shall not be in line with the slots of the next succeeding course to be applied.

It is to be observed that where thirty-six by thirteen inch strips are laid with a six inch exposure and a one-inch head lap to provide a brick wall simulating covering for one hundred square feet of surface to be protected, only two-hundred and sixteen square feet of material is required. In view of the foregoing it is apparent that a minimum amount of material is required, and that by employing a two course brick shingle strip embodying my invention there is approximately a 7.4 per cent saving in material.

Another advantage of my invention resides in the reduction, for any given number of courses in a unit area, of the horizontal exposed edges:

which may be blown upwardly by the wind and which are susceptible to other adverse influences by the weather.

Although I have specifically described my invention in conjunction with a shingle strip, this is by no means to limit the scope of my invention. Some of the other possible modifications of my invention are a shingle strip of indefinite length and constituting what is generally known in the trade as roll roofing; a laminated structure consisting of a suitable base having adhesively secured thereto by asphalt or similar adhesive composition a building strip whose entire upper face is divided into a plurality of brick simulating courses with the usual mortar joint simulations therebetween as shown in the lower portion of Figures 2 and 3; and a shingle strip or roll roofing whose entire upper face is divided into a plurality of brick simulating courses with the usual mortar joint simulations therebetween. The last mentioned modification may be applied directly to a side wall whose face is similar in color to that of the mortar joint simulating areas, or whose face may be first coated with a bituminous adhesive before the application of said element. Moreover, I do not wish to be limited to the number of brick simulating courses in each strip, and I have described a two course brick simulation as a convenient means of illustration. I appreciate that where the head lap is constant and the number of brick simulating courses in each strip is greater than two, the amount of material required to cover one-hundred square feet of surface is lessened.

35 I claim as my invention:

1. A covering sheet for laying on a surface in overlapping arrangement comprising a base having the portion thereof intended to be exposed demarcated by a plurality of parallel stripes across the sheet and by cuts in the base extending transversely to the stripes into areas simulating bricks laid in a plurality of courses with the vertical joints of one course offset from the vertical joints of the adjacent courses, the ends of said exposed portion of the sheet being cut in the offset form along the lines of the end brick simulating areas of the sheet but having for each simulated horizontal joint at an end thereof a portion of the base extending beyond the end of an end brick simulating area to provide an abutment against which to abut the end of a similar sheet so as to leave spaces between the ends of the sheets to simulate vertical joints of brickwork.

2. A covering sheet for laying upon the surface of a wall in overlapping arrangement with similar covering sheets which comprises a base, a plurality of parallel stripes extending across the exposed portion of the sheet and spaced apart distances equivalent to the depth of a brick to simulate horizontal joints of brickwork, cut-outs in said base extending between said stripes at right angles thereto and having the width of and being spaced apart in the direction of the stripes distances to simulate the vertical joints of brick work, the ends of said exposed portion of the sheet being cut in stepped arrangement along the simulated brickwork joints, the portions of the base upon which are simulated the horizontal brick joints being extended beyond the end of an adjacent brick simulating area in the direction lengthwise of said horizontal joint for a distance equal to the width of the vertical joint and with a height equal to the width of the horizontal joint whereby an abutment is formed against which the opposite end of a similar sheet may be laid

and thereby a space is left between portions of the end edges of adjacent sheets to simulate the vertical brick joint at the end of said sheet.

3. A covering sheet for laying upon the surface of a wall in overlapping arrangement with similar covering sheets which comprises a base of impervious material and having extending across the portion of the sheet to be exposed a plurality of parallel stripes and having cuts in the base between the stripes in staggered arrangement simulatively to demarcate the bricks and to simulate respectively the horizontal and the vertical joints of brickwork laid in courses, the ends of the sheets being cut in stepped form along said simulated joints, the end of the portion of the sheet to be overlapped being in stepped relation to the cuts simulating the vertical joints of the brickwork.

4. A covering sheet for laying upon a surface in overlapping arrangement with similar covering sheets which comprises a base having upon the portion to be exposed thereof a simulation of masonry units laid in a plurality of courses with longitudinal and transverse mortar joints therebetween, the end of the portion to be overlapped of said sheet being on a line which if extended would pass intermediate the simulating transverse joints of the masonry, the longitudinal length of said portion to be overlapped being greater than the longitudinal length of the portions of the sheet which simulate the courses of masonry by an amount equal to the width of a transverse mortar joint.

5. A covering sheet for laying upon a surface in overlapping arrangement with similar covering sheets which comprises a base having upon the portion to be exposed thereof a simulation of masonry units laid in a plurality of courses with longitudinal and transverse mortar joints therebetween, the end of the portion to be overlapped of said sheet being on a line which if extended would pass intermediate the simulating transverse joints of the masonry, and longitudinal length of said portion to be overlapped being greater than the longitudinal length of the portions of the sheet which simulate the courses of masonry by an amount equal to the width of a transverse mortar joint, the length of the simulated longitudinal joint being also greater than the longitudinal length of said portions of the sheet simulating courses of masonry by an amount equal to the width of a transverse joint.

6. A covering sheet for laying upon a surface in complementary arrangement with similar covering sheets which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries of said area being at the ends of the sheet and completing an outline at said ends having a stepped form rising at each end in the same direction longitudinally of the sheet.

7. A covering sheet for laying on a surface in overlapping arrangement including a portion thereof to be overlapped comprising a base having at least a part of the surface thereof demarcated by at least one stripe across the sheet and by cuts in the base extending transversely to the stripe into areas simulating masonry units laid in a plurality of courses with mortar joints therebetween in offset arrangement, the ends of said

sheet transverse to said stripe being of the stepped form of the offset arrangement of the joints of the masonry as provided by cuts along the stripe, each joining two transverse cuts, and the edges of said portion to be overlapped being not in line with the lines of said simulated joints in the exposed portion.

8. A covering sheet for laying on a surface in overlapping arrangement including a portion thereof to be overlapped comprising a base having at least a part of the surface thereof demarcated by at least one stripe across the sheet and by cuts in the base extending transversely to the stripe into areas simulating masonry units laid in a plurality of courses with mortar joints therebetween, the ends of said sheet transverse to said stripe being cut in such stepped form corresponding to that of the joints of the masonry that cuts in the areas simulating the masonry units are avoided, the end edges of the sheet and the edges joining one stepped end edge with another being along the line simulating respectively the end edge and a lengthwise edge of a masonry unit, and the edges of said portion to be overlapped being not in line with the lines of said simulated joints in the exposed portion.

9. A covering sheet for laying upon a surface in complementary arrangement with similar covering sheets and with a portion of its surface overlapped which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries of said area being at the ends of the sheet and completing an outline of said end having a stepped form, said transverse outline conforming to the transverse joints of the masonry, and an edge of said portion to be overlapped being not in line with the lines of said simulated joints in the exposed portion.

10. A covering sheet for laying upon a surface in complementary arrangement with similar covering sheets and with a portion of its surface overlapped which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries of said area being at the ends of the sheet and completing an outline of said end having a stepped form, said transverse outline conforming to the transverse joints of the masonry and extending along the end edges of the end masonry units in each course, and an edge of said portion to be overlapped being not in line with the lines of said simulated joints in the exposed portion.

11. A covering for laying upon a surface upon which is simulated a plurality of courses of masonry units, said simulated masonry units being provided by discontinuous longitudinal transversely spaced stripes having a surface character simulating the masonry units, said discontinuous stripes being separated by continuous longitudinal stripes having a surface of a character contrasting with that of said discontinuous stripes to simulate the longitudinal joints of masonry, said covering having cuts therein extending transversely of said continuous longitudinal stripes and dividing said discontinuous stripes into a series of areas simulating the masonry units, said cuts being so formed as to simulate the transverse joints of the masonry, said covering having the edge thereof extending generally transversely of the longitudinal dimension of the covering cut longitudinally along the longitudinal joints and transversely along the transverse joints of the masonry.

12. A covering sheet for laying upon a surface in complementary arrangement with similar covering sheets, which comprises a base having upon at least a portion of the surface thereof a simulation of masonry units laid in a plurality of courses with mortar joints therebetween, the longitudinal boundaries of said portion of the surface extending along lines within the simulated longitudinal joints of the masonry, the transverse boundaries of said portion extending along lines within the simulated transverse joints of the masonry and completing an outline for said portion having an offset form.

13. A covering sheet for laying upon a surface in overlapping arrangement with similar covering sheets, having demarcated on the portion thereof to be exposed a simulation of a plurality of courses of masonry units laid with joints therebetween, the transverse joints of the masonry being simulated by cutouts in the sheet exposing therethrough the surface of an overlapped portion, which overlapped surface has its extent in a direction transverse to the courses greater than the extent in said direction of the portion simulating the plurality of courses with the joints therebetween and including a longitudinal joint above the topmost course simulated on said sheet, whereby a multiple ply covering with a headlap may be laid upon the surface when the edge to be exposed of an overlapping sheet is laid a distance above said topmost simulated course a distance equal to the width of a longitudinal joint, the ends of said sheet having a form coinciding in the exposed portion of said sheet with the simulated masonry joints upon the sheet, and the end edges of the overlapped portion thereof being not in line with the lines of said simulated joints in the exposed portion.

JULES L. WETTLAUFER.
